UNITED STATES PATENT OFFICE.

ANDREW JAY REAMS, JR., AND LEWIS A. WILLIAMS, OF KALAMAZOO, MICHIGAN.

DESIGN FOR A MUSICAL INSTRUMENT.

51,025.

Specification for Design.

Patented July 10, 1917.

Application filed March 14, 1917. Serial No. 154,878. Term of patent 14 years.

To all whom it may concern:

Be it known that we, ANDREW JAY REAMS, Jr., and LEWIS A. WILLIAMS, citizens of the United States, residing in Kalamazoo, county of Kalamazoo, State of Michigan, have invented a new and ornamental Design for Musical Instruments, of which the following is a specification, reference being had to the accompanying drawing, forming a part thereof.

Figure I is a plan view of the body of

a musical instrument showing our improved design.

Fig. II is a perspective view thereof.

We claim:

The ornamental design for a musical instrument, as shown.

ANDREW JAY REAMS, JR.
LEWIS A. WILLIAMS.
